Walter M. Fuller
ATTORNEY

UNITED STATES PATENT OFFICE.

HORACE H. WELCH, OF CHICAGO, ILLINOIS.

GEM.

1,421,329.

Specification of Letters Patent. Patented June 27, 1922.

Application filed January 5, 1921. Serial No. 435,075.

To all whom it may concern:

Be it known that I, HORACE H. WELCH, a citizen of the United States, residing at Chicago, in the county of Cook and State 5 of Illinois, have invented certain new and useful Improvements in Gems, of which the following is a specification.

My invention pertains to a novel and pleasing type of gem or jewel adapted for 10 many and varied uses, particularly in the production of jewelry.

Its salient and outstanding characteristic resides in its capacity for automatically and more or less radically changing and modifying 15 its appearance by reason of its changes of position, such as are imparted thereto by the movements of the hand of the wearer when the gem is incorporated, for example, as a part of a ring, or in the handling of the 20 beads of a string when the gems constitute such beads.

By reason of its readily changing appearance, the gem is especially attractive and commands the attention and approval of the 25 observer.

In its embodiment in physical form, the invention comprises the employment of a transparent or translucent hollow shell or bead, such as glass, loosely housing or enclosing 30 one or more display elements, such as the well-known sparkling granular "metallics" of the trade, or other attractive members, such for instance as crumpled pieces of gold leaf, tinsel, or the like.

35 In some forms of the gem, it is desirable to fill the hollow body with liquid and to enclose the display elements in such liquid, whereby to prevent their wear or reduction in size by their attrition on one another and 40 to facilitate their change of position.

In many instances, it is preferable to so choose the specific gravity of the liquid employed with reference to the weight of the display elements per unit volume, that the 45 latter will readily or almost float, whereby when once disturbed as by the movement of the encasing shell, they will settle slowly and in so doing rearrange their positions at the same time enhancing or increasing their 50 attractive display qualities.

In some embodiments it is well to have the exhibit particles of different colors or dissimilar physical characteristics, the liquid being clear or colored, and the shell may be

of clear glass or of suitable color as may 55 be preferred to heighten the beauty of the displayed contents.

To enable those skilled in this art to have a full and complete understanding of the invention and its various benefits and advantages, I have illustrated in the accompanying drawing, forming a part of this specification, several embodiments of the invention, and throughout the several views of such drawing like reference characters 65 refer to the same parts.

In the drawing:

Figure 1 is a face view of a ring fitted with one of the new gems;

Figure 2 is a central section through one 70 of such gems on an enlarged scale;

Figure 3 is a rear face view of the gem;

Figure 4 illustrates a modified style of the 75 gem in section forming part of a ring shown in dotted lines;

Figure 5 portrays a further modified type of the article;

Figure 6 shows a portion of a string of beads; and

Figure 7 illustrates a ring fitted with one 80 of the gems not filled with a liquid.

By reference to the drawing, particularly Figure 1, it will be observed that the novel gem or jewel 11 is desirably, but not necessarily, of substantially spherical shape and 85 is secured in the customary ring 12 by means of the usual jewel-retaining prongs 13.

Such gem or jewel is illustrated in greater detail in Figures 2 and 3 wherein it will be seen that the article comprises a globular 90 or orbicular glass shell or casing 14 enclosing a suitable body of liquid 15 in which is immersed or incorporated a number of display elements 16, 16 of irregular or uneven or unsymmetrical shape, such, for example, as 95 crumpled or wrinkled glittering or scintillating pieces of gold or silver leaf or similar iridescent or glistening bodies, and the liquid is desirably, although not necessarily, of such specific gravity as to maintain such enclosed 100 bodies more or less in suspension or floating condition whereby when these shiny or brilliant bodies are temporarily disturbed by the movement of the gem they will settle to the bottom of the glass enclosure somewhat 105 slowly or gradually and in so doing will rearrange their positions, thus at all times presenting an attractive and pleasing ap-

pearance by reason not only of their original brilliant radiating characteristics but also by their movements.

It is convenient to supply such encasing 5 glass globe or sphere with an inwardly extended glass air-tube 17 sealed liquid-tight in the body 14 and adapted to contain a small bubble of air incident to the production of the device and which is retained in 10 such tube thus avoiding its escape and possibly detrimental appearance in other portions of the body.

The modification of the invention illustrated in Figure 4 omits the tube 17 and 15 instead of employing thin sheets or leaves of gleaming or flashing display material, the latter is of more granular form, as illustrated at 18. For this purpose the well-known colored twinkling shiny "metallics" 20 of the trade may be suitably employed and they may be of all the same color or of different tints or colors as may be preferred.

In both of these embodiments of the invention and the others described hereinafter, 25 the liquid may or may not be employed, but in many cases it is well to use it because it saves wear on the multitude of tiny iridescent or lustrous display members and retards their movements so as to keep them in suspension or floating condition longer than 30 would otherwise occur and hence augmenting their sparkling or nacreous characteristics.

In all of the several embodiments the glass bead or shell may be clear or colored, and 35 the liquid which it encloses may be clear or colored as may be desired or as circumstances dictate.

In Figure 5 a somewhat different embodiment is illustrated and in this case the glass 40 or similar transparent shell 14 houses a liquid 15 which contains a single loose gem 19 which may be of any shape desired and which, because of its loose association with the member 14, is of increased beauty because 45 it may display to the observer many features which would otherwise be concealed, for example the body 19 may be an opal or pearl, or piece of mother of pearl or similar jewel, which, because of its capability of movement, is much more attractive and pavonine than if it were firmly mounted in the ring or other piece of jewelry with which it is associated.

In Figure 6 I have shown the new ball-like globular gems employed as beads on a string 20 which passes through glass tubes 21 extended through and sealed in the enclosures 14, the latter containing the one or more twinkling or sparkling display elements, and, if preferred, a liquid of suitable specific gravity may be used to facilitate their movements and to prevent their wear.

In Figure 7, a ring is shown fitted with one of the gems comprising a hollow, transparent or translucent or colored container

30 such as glass, housing a number of brilliant display bodies 31. Such element 30 contains no liquid, the particles 31 being loosely housed in and only partially filling the hollow body and capable of movement 70 therein to augment their attractive display qualities.

Obviously the invention is not limited and restricted to the precise and exact embodiments presented, but rather is susceptible 75 of a variety of incorporations in physical form and the devices shown may, of course, be changed in many respects without departure from the heart and essence of the invention and without the sacrifice of any of 80 its substantial benefits and advantages.

Although the globular enclosing shell has been characterized as transparent, it may be merely translucent or semi-transparent only if more desirable to partially conceal 85 the encased display members, and it is intended to cover all such changes as fairly fall within the scope of the appended claims, wherein the term transparent may be interpreted to mean fully or partly transparent.

I claim:

1. A finger ring having a setting, an artificial gem secured therein, said gem comprising a hollow body, and a sufficient number of loose brilliant display elements housed and movable in said body to give to the gem as a whole the appearance of internal mobility upon movement of the gem, said body being sufficiently translucent to 95 render visible therethrough the moving brilliant display elements.

2. An article of jewelry to be worn on the person including an artificial gem, said gem comprising a hollow body and a sufficient 105 number of loose brilliant display elements housed and movable in said body to give to the gem as a whole the appearance of internal mobility upon movement of the article, said body being sufficiently translucent to 110 render visible therethrough the moving brilliant display elements.

3. An article of jewelry to be worn on the person including an artificial gem comprising a hollow body, a liquid in said body 115 and a sufficient number of loose brilliant solid display elements in said liquid to give to the gem as a whole the appearance of internal mobility upon movement of the article, said body being sufficiently translucent to render visible therethrough the moving brilliant display elements.

4. An article of jewelry to be worn on the person including an artificial gem, said gem comprising a hollow body, a colored liquid in said body and a sufficient number of loose brilliant solid display elements in said liquid to give to the gem as a whole the appearance of internal mobility upon movement of the article, said body being 125 130

sufficiently translucent to render visible therethrough the moving brilliant display elements.

5. An article of jewelry to be worn on the person including an artificial gem, said gem comprising a hollow colored body, a liquid in said body, and a sufficient number of loose brilliant solid display elements in said liquid to give to the artificial gem an appearance 10 of internal mobility upon movement of the article, said body being sufficiently translucent to render visible therethrough the moving brilliant display elements.

6. An article of jewelry to be worn on the person including an artificial gem, said gem comprising a hollow transparent body, a transparent liquid in said body and a sufficient number of loose colored brilliant solid display elements in said liquid to give to 20 the gem as a whole the appearance of internal mobility upon movement of the article.

7. An article of jewelry to be worn on the

person including an artificial gem, said gem comprising a hollow body, and one or more fragments of a precious stone housed and 25 movable in said body thereby enhancing the beauty of said fragment or fragments by reason of movement of the latter in said body upon movement of the article, said body being sufficiently translucent to render 30 visible therethrough the said fragment or fragments.

8. An article of jewelry to be worn on the person comprising in combination a hollow body, a liquid in said body, and one or more 35 precious stones immersed and movable in said body thereby enhancing the beauty of said precious stone or stones by reason of movement of the latter in said liquid upon movement of the article, said body being 40 sufficiently translucent to render visible therethrough the said precious stone or stones.

HORACE H. WELCH.
